UNITED STATES PATENT OFFICE

2,590,652

SPEED FEED MANIFOLDING ATTACHMENT
FOR TYPEWRITERS

Herman F. Sadgebury and Robert N. Ward, Dayton, Ohio, assignors to The Egry Register Company, Dayton, Ohio, a corporation of Ohio

Application June 29, 1948, Serial No. 35,794

3 Claims. (Cl. 197—126)

1

This invention relates to speed feed manifolding attachment for typewriters and other typewriting machines having a movable carriage provided with a platen for translation past a fixed typing location.

More particularly, the present invention deals with a manifolding attachment adapted for use with various types and makes of typewriters, and so arranged that it may be easily attached and detached whereby a given typewriter or other typewriting machine may be made available for manifolding and/or other work.

The manifolding attachment of this invention is particularly characterized by the fact that it does not interfere in any way with operational parts of the typewriting machine, it being attachable to a reciprocating portion or member of the typewriting machine which is not an operational part.

The invention resides in a mounting structure for supporting the manifolding attachment in cooperating relationship with the carriage of a typewriter or similar machine, the manifolding attachment being supported independently of the typewriter but connected to the carriage for translation in unison with it; moreover, the mounting structure is so arranged that the manifolding attachment may be disconnected from the carriage and lowered to an inoperative position in order that the typewriter may be utilized for normal typing operations when the manifolding apparatus is not required.

These advantages are brought about by providing a base member which is arranged to be placed upon the surface of the typewriter desk with the typewriter resting upon it so that the weight of the typewriter itself holds the base and manifolding attachment firmly in position. The base structure rises upwardly at the rear of the typewriter, adjacent its carriage, and is provided with a pair of spaced horizontal tracks which support a horizontally movable manifold carriage, the manifold attachment being mounted upon the carriage and rising above the platen of the typewriter so as to guide and feed the manifold sheets downwardly to the platen. The manifold carriage at opposite ends includes releasable contact arms which extend toward and contact the opposite ends of the typewriter carriage so that the translatory movements of the typewriter carriage are transmitted directly to the manifold carriage, causing the manifolding apparatus to move in unison with the carriage during the typing operations.

Standard typewriters vary from model to model 65

2

in the width dimension of the machine or its carriage and also as to the spacing or depth of the carriage with respect to the rearward edge of the machine frame. A distinctive feature of the present structure resides in provisions by which the manifolding attachment can be made to accommodate such factors by suitable adjustments but without any refabrication. In other words, by making certain adjustments in the width of the attachment and its connection to the typewriter carriage, the attachment is capable of being applied to practically any commercial typewriter.

The objects and advantages of the present invention will be readily apparent to those skilled in the art; however, the nature and scope of the present invention and a manner in which it may be employed advantageously in a typical embodiment thereof will be fully understood from the following description taken in connection with the annexed drawings, wherein:

Fig. 1 is a perspective view showing the manifolding frame mounted on its carriage and supported on its base;

Fig. 2 is a perspective view showing the manifolding frame mounted on its carriage and supported on its frame in operational position with respect to a typewriter;

Fig. 3 is a front elevational view showing a portion of the manifolding frame and the contact arms extending therefrom;

Fig. 4 is a side elevational view of a portion of the manifolding frame showing the contact arms extending therefrom, the bracket mounting the frame on its carriage, and the safety hook which prevents tilting;

Fig. 5 is a front elevational view of the manifolding frame carriage mounted on its base;

Fig. 6 is a view showing the manner in which the carbon sheets are supported interleaved between strips of paper written upon;

Fig. 7 is a longitudinal section in side elevation of the manifolding frame, showing the strips of paper with the carbons interleaved therebetween after the strips and carbon sheets have been withdrawn so that the strips may be fed for severing purposes;

Fig. 8 is a view similar to Fig. 7 but with the strips of paper and the carbon sheets in the position they assume at the close of each writing period;

Fig. 9 is an enlarged view showing the means for aligning the strips of paper in aligning position;

Fig. 10 is a section through parts of strips

showing the aligning means with the aligning pin withdrawn from the holes in the strips of paper;

Fig. 11 is a view similar to Fig. 8 but showing the strips of paper and the carbon sheets in the position they assume at the beginning of the writing period;

Fig. 12 is a section taken along the line 12—12 of Fig. 11;

Fig. 13 is a detail view showing the aligning bar with aligning fingers for engaging the creases in the paper to align the strips of paper;

Fig. 14 is a front elevational view of the manifolding frame showing parts of the carbon sheets;

Fig. 15 is a section taken along the line 15—15 of Fig. 7;

Fig. 16 is a rear elevation of the aligning part of the manifolding frame;

Fig. 17 is a view showing in side elevation the upper end of the manifolding frame with the spring casing in section;

Fig. 18 is a front view of the manifolding frame with the strips of paper and the carbon sheets retracted into the upper position; and

Fig. 19 is a view similar to Fig. 18 showing the strips of paper and the carbon sheets at the end of the writing period.

In the drawings, like numerals refer to like parts throughout.

Referring to the drawings in more detail, it will be noted that the manifolding frame consists of two lateral members 21 which have internally directed flanges 22 which act as supports and guides for the carbon carrier plate (Fig. 6). These lateral members are connected by two transverse members 23, connected to the lateral members by bolts 24.

For the purpose of attaching the transverse members to the lateral members the ends of the transverse members are turned in to engage the lateral members. These transverse members are braced by means of two diagonal braces 25, each having its ends riveted by rivets 26 to the transverse members as in Fig. 14 or, alternatively directly to the lateral members, as in Fig. 3. Where these braces cross they are connected by a rivet 27 (Fig. 18), or they may be brought together and spot welded as in Fig. 1.

On the lower end of each lateral member is a bracket 28 having a rearwardly extending portion 29, and said portion 29 is attached to an upright 30 mounted on the carriage 84 (Fig. 5). The upright 30 mounted on the right side of the carriage 84 (as viewed in Fig. 5) is provided with an outwardly turned ear 31 provided with a stop 31a and adapted to be engaged by a hook 32 which is swingably mounted on the portion 29 of the bracket 28 by a stud 33. The hook 32 prevents back-tilting of the frame during use, but may be easily released to permit tilting back of the frame when not in use. The stud 34 mounts the portion 29 of the bracket 28 on the upright 30, and acts as a fulcrum or bearing to permit tilting of the frame when desired. A two-piece shaft 35 telescopes within a hollow shaft 35a which extends across the back of the frame from the brackets 28, 29 mounted on each lateral member (Fig. 3). Each end of the shaft 35a is provided with a bushing 36 and wing nut 36a arranged to maintain the sections of the shaft 35 in predetermined extension according to the width of the body of the typewriting machine on which the frame is to be used.

The typewriter illustrated has the usual platen 37a and the usual paper release rollers 37b (Fig. 7). On the lower end of the frame and supported

by the lateral members is a shaft 38 (Fig. 14) which has thereon two spaced sprocket wheels 39. In the upper end of the frame and supported by the lateral members is a shaft 40 which has thereon two spaced sprocket wheels 41. The sprocket wheels on the shaft 38 are connected to the sprocket wheels on the shaft 40 by means of sprocket chains 42.

Between the sprocket wheels 41 is a drum 43 forming a roller over which superimposed strips of paper pass. On each end of the drum adjacent a sprocket wheel 41 is a guide disc 43a which aids in aligning the strips of paper and holding them in alignment laterally as they pass over the roller during the operation of the typewriter. On the upper end of one of the lateral members is a housing or casing 44 which fits over one end of the shaft 40. This housing is supported on the lateral member by means of screws 45, and has therein a spring 46, one end of which is attached to the housing while the other end is attached to the shaft 40.

A carrier plate 47 extends across the front of the frame and is supported by the inturned flanges 22 and is attached to the chains by means of bolts 48. On each end of the carrier plate is a bracket 49 attached thereto by means of a rivet 50 which fits behind the inturned flange and prevents the carrier plate from leaving the frame (Fig. 12). Between each bracket 49 and the carrier plate is a spacer 51. On each spacer, the carrier plate and the bracket 49 is a pin 52. These pins serve to support carbon carriers 53, each of which has at each end a hole surrounded by reenforcing material 54 to prevent wear due to engagement with the pin.

There may be any desired number of these carbon carriers, which are held in position by means of a spring plate 56, which has in each end a notch 57 adapted to engage in suitable notches 53 in the pins 52. As shown in Figs. 11 and 12, each of these pins has a plurality of these notches, whereas in the form shown in Figs. 6 and 15 each pin has one notch, and in order to take up the slack between the spring plate 56 and the outer carbon carrier, a sleeve 55 is provided for each pin. It is found more desirable, however, to use the plurality of notches rather than to use one notch with the sleeve 55.

The strips of paper are indicated by the numeral 59 and may be fed from a pile located at some suitable point behind the typewriter, and fed over the top of the drum or roller and beneath the platen of the typewriter. The carbon sheets 60 interleaved between the strips of paper are supported by means of the carbon carriers 53, one carbon sheet for each carbon carrier. On each lateral member, near the typewriter, is a guide plate 61 to prevent lateral movement of the sheets of paper as they are fed to the typewriter.

Attached to the chains at the back of the frame is a plate 62, which has at each end, at its upper edge, an ear 63 (Figs. 7 and 9). These ears are connected by a rod 64 which serves to hold the sheets of paper in assembled condition. At each end and intermediate the lateral edges of the plate 62 is an ear 65. These ears are connected by a rod 66, similar to the rod 64 and used for a similar purpose. At each end and at the lower edge of the plate 62 is an ear 67, to which is attached one end of a lever 68 by means of an ear 70 formed on a lateral flange 69, and a bolt 71 passing through the ears 67 and 70.

The other end of this lever is bent to form a stop flange 72, which engages the plate 62 when

the aligning pins 74 are in the holes in the paper for aligning the strips of paper. There are two of these levers, one at each end of the frame and at the rear thereof, connected by means of an angle bar 73 which extends to each side of the frame and may be gripped for releasing the pins from the holes in the strips of paper. The holes in the strips of paper are indicated by the numerals 75.

In the form shown in Figs. 11 and 12 there is provided at each side of the frame a guide plate 76 attached at each end to one of the transverse members 23. In order to hold the plate 62 against the guide plates there is provided at each end of the plate 62 a clip 77 which fits in front of the guide plate and holds the plate 62 in contact with the back surfaces of these guide plates. A spring 78 is provided for holding the pins against the sheets of paper or in the holes in which they project for aligning purposes. These springs are attached to the angle bar 73 and the guide plate 76.

There is also provided in one of the lateral members an adjustable clip 80 for use in determining when the holes in the strips of paper are in a position to receive the aligning pins. The strips of paper are separated into separate tear-off sheets by means of creases or perforations 81, extending transversely across the strips of paper.

Each strip of paper is divided into sheets of the same size by the transverse creases. The distance between the upper edge of each sheet of paper and the aligning holes is the same for all sheets and for all strips of paper composed of sheets. Instead of using aligning pins for entering the aligning holes 75 there may be provided on the angle bar 73, fingers 82 which will engage the strips in the creases (Fig. 13).

The numeral 83 represents a box of paper resting on a table at the rear of the typewriter. While a box is illustrated, none is required, and the paper stack may rest on the table top after being removed from its shipping box. This paper is composed of a plurality of superimposed strips folded along the creases. These superimposed strips of paper are fed over the roller or drum and beneath the platen of the typewriter. The aligning pins and the plate carrying these pins are located on the sprocket chains at the rear of the manifolding frame, so that the aligning is accomplished before the strips pass over the roller or drum, at the upper end of the frame.

In passing over the roller or drum at the upper end of the frame the strips become partially out of alignment, due to the variation in the diameters or curvatures of the strips. However, this lack of alignment is removed or compensated for by passing the strips beneath the platen of the typewriter, where the curvature of the strips varies inversely as they vary in passing over the drum. By this means the holes of the strips are in alignment after the strips have been fed around the platen. This is illustrated in Fig. 11, which shows the holes 75 in the strips in perfect alignment after the strips have passed beneath the platen.

The purpose of this accurate alignment is that the writing on each superimposed sheet of the various strips corresponds in place and position to that of each of the others. During the process of writing the strips with the interleaved carbon sheets therebetween are fed for writing purposes. The free ends of the strips of paper, as shown in Fig. 11, move upwardly during the process of writing. After writing has been finished the

paper release is operated to relieve pressure holding the strips of paper against the platen. The aligning elements are sufficient to withdraw the strips and the carbon sheets from about the platen.

When the carbon sheets and strips of paper have been withdrawn to the position shown in Fig. 7, the carbon sheets are above the platen, while the strips of paper are in a position to be gripped and held against the platen. The paper release is brought into a position to hold the strips of paper against the platen. The angle bar 73 is pushed backwardly to withdraw the pins from the holes in the strips of paper. The platen is rotated to feed the strips of paper forwardly. This feeding operation continues until the creases at the lower ends of the next sections of the strips to be written on have reached the point indicated by the clip 80, at which time the bar 73 is released and the pins drop into the holes of the strips. Any further rotation of the platen will not only cause the strips of paper to be advanced, but also the sheets of carbon interleaved therebetween. When the platen has been rotated sufficiently to bring the creases onto the platen, the writing parts of the strips of paper are torn off. The platen is further rotated to adjust the oncoming sections of the strips of paper for writing purposes.

During this entire operation the paper has been touched by the hand of the operator only for the purpose of severing the used sections from the strips. By adjusting the stops 79 and the clip 80, the strips of paper divided into sheets of various lengths may be used.

As will be noted by reference to Fig. 1, the frame is mounted by means of the brackets 28, 29 and the upright 30 on a movable carriage 84 arranged to move from side to side in unison with the carriage of the typewriter. Two-piece extensible contact arms 84a are provided at each end of the extensible shaft 35. A wing nut 84b fixes the relationship of the two parts of the arm 84a. These contact arms, as shown in Fig. 2, are fixed by contact against a non-operational portion of the typewriter carriage, so that while thereby the carriage 84 and frame mounted thereon are caused to move from side to side according to like movement of the typewriter carriage, there is no interference with any operational part of the typewriter.

As shown in Fig. 5, the carriage 84 is mounted on a pair of tracks 85 by means of wheels 86. The tracks 85 are supported on an X-frame 87 which is mounted on a pair of posts 88 arranged slidably to move through bushings 89, each of which is provided with a lock screw (not shown). The bushings 89 are mounted on upwardly extending wings 90 of the base member or apron 91 which is arranged to receive the base of the typewriter and to be held in position thereby.

Fig. 4 illustrates the manner in which the frame may be separated from the typewriter without necessarily disturbing either the frame or the typewriter. The wing nuts 84b are loosened, thus permitting the contact arms 84a to move away from the carriage of the typewriter in the position or direction desired. This disengages the frame from the typewriter. The hook 32 is then lifted to disengage it from the ear 31 of the upright 30, whereupon the frame may be caused to tilt backward by swinging the brackets 28, 29 upwardly and thence backwardly using the stud 34 as fulcrum, until the lip 29a of the bracket portion 29 comes in contact with the stop 31a, whereby the frame will be held in an inclined

position extending outwardly to the rear of the typewriter and above the desk top, where it will not interfere in any way with the operation of the typewriter or the use of the desk. When it is desired again to make use of the frame, it is moved upwardly and thence frontwise from its inclined position using the stud 34 as fulcrum, and then brought into position where the hook 32 again engages the ear 31. The contact arms are then extended and brought into contact with the carriage of the typewriter, the wing nuts 84b are made tight, and the frame is ready for use.

Referring again to Fig. 5, it will be noted that the frame 84 is provided with two protrusions 92 adapted to act as stops to prevent overriding. A latch 93 is affixed along the bottom surface of the lower track 85, and this latch will prevent over-riding by stopping travel of the frame 84 in either direction when travel has reached the point indicated by the corresponding protrusion 92. By moving the latch backward, either of the protrusions 92 may be permitted to pass, thus providing means for removing the carriage 84 from the tracks 85 when such removal is desired.

As those skilled in the art will fully comprehend, the combination of the base member or apron 91 and carriage 84 finds application, with or without the frame of this invention, in many other combinations than with a typewriter; however, such other uses need not be discussed here.

Those skilled in the art will also appreciate fully that the present invention provides an economical, practical, flexible, new and novel attachment for speed feed manifolding; and they will understand the many advantages which the present invention offers as compared with previous attempts to solve the problems here involved.

While the present invention has been described herein in certain specific embodiments, it has not been intended thereby to have the present invention limited to or circumscribed by the specific details of construction, arrangement of parts, operation, procedures, materials and the like herein described or illustrated in the annexed drawings; it being understood that the present invention is susceptible to modification according to individual conditions and preference without necessarily departing from the spirit of this disclosure and the scope of the appended claims.

We claim:

1. The combination with a manifolding frame for a typewriting machine of a base comprising an apron arranged to receive said machine and be maintained in position thereby and a pair of post receiving bushings, a movable carriage provided with post members arranged to be positioned in said post receiving bushings in selective elevational arrangement whereby to mount said carriage on said base, said carriage being provided with roller means for movement thereof from side to side, means extending from said frame mounting said frame on said carriage in tiltable arrangement, extensible shaft means in association with said mounting means, and means extending from said frame arranged to contact a

non-operative reciprocating member of said machine whereby to cause movement of said frame from side to side in unison with the normal reciprocating movement of said member, said last mentioned means comprising a pair of 2-piece extensible arm means mounted at both ends of said extensible shaft means.

2. The combination with a manifolding frame for a typewriting machine of a base comprising an apron arranged to receive said machine and a pair of post receiving bushings, track means mounted on post members arranged to cooperate with said post receiving bushings in selective elevational position, carriage means provided with roller means arranged in association with said track means whereby said carriage means may move from side to side, means extending from said frame mounting said frame on said carriage means in tiltable arrangement, extensible shaft means in association with said mounting means, and means extending from said frame arranged to contact a non-operative reciprocating member of said machine whereby to cause movement of said frame from side to side in unison with the normal reciprocating movement of said member, said last mentioned means comprising a plurality of extensible arms one mounted at each end of said extensible shaft means.

3. The combination with a manifolding frame for a typewriting machine of a base adapted to be held in position by the weight of the said machine and provided with a pair of post receiving bushings, track means provided with a pair of post means mounted on said base in association with said post receiving bushings, carriage means having a plurality of grooved rollers mounted on said track means, means mounting said frame in operational relationship with said carriage means comprising a pair of tiltable bracket members, extensible shaft means in association with said bracket members, means arranged to cause said frame, said carriage means and a reciprocating part of said machine to move in unison from side to side in normal translation comprising a pair of extensible arms mounted one at each end of said extensible shaft means, and means for feeding interleaved sheets from said frame to said machine.
